George R. Taylor

UNITED STATES PATENT OFFICE.

GEORGE R. TAYLOR, OF LOUISVILLE, KENTUCKY.

PROPELLING CANAL-BOATS.

SPECIFICATION forming part of Letters Patent No. 298,135, dated May 6, 1884.

Application filed March 16, 1883. (No model.)

To all whom it may concern:

Be it known that I, GEORGE R. TAYLOR, of Louisville, in the county of Jefferson and State of Kentucky, have invented certain new and 5 useful Improvements in the Method of Propelling Canal-Boats, the following being a full and accurate specification thereof, reference being had to the accompanying drawings.

Like letters indicate like parts.

10 Figure 1 is a side view, and Fig. 2 represents a section of the wire rope. Fig. 3 represents a plan view of the truck or bearing with a wire rope passing through its axle, with the connecting metallic bar *a*. Fig. 4 represents 15 the device for attaching the boat-cable to the propelling device or endless rope. Fig. 5 represents an improved capstan for receiving the towing-cable and giving off the same with the required resistance. Fig. 6 represents a plan 20 view of my improved capstan.

My invention relates to means for economizing in the cost and increasing the speed of moving canal and other boats in ordinary canal-channels. To do this I erect on the banks of 25 the canal at proper intervals posts or brackets, with their upper ends projecting over the channel of the canal, and on the said projecting ends of the brackets over the water I construct a continuous track from bracket to bracket to 30 any convenient length or section of the canal, as will hereinafter appear. The said track consists of an upper and a lower passage-way, each being provided with rails, on which a two-wheeled truck may run. The said ways may 35 be located one directly above the other or horizontally on the side of each other, and the track may be so constructed that the same endless rope may convey the boats both directions, or one way or track may be on one side of the 40 canal and the other way on the other side of the canal. In the drawings I show and prefer to describe the ways above each other. The lower way is suspended or held on the under side of the said brackets in such manner that a free 45 opening is formed from below and between the rails of the track, so that the towing-cable from the boat can be readily attached to the trucks running on the said rails or track. An endless rope is carried upon the said trucks, to 50 which it is firmly attached. The towing-cable is attached to the endless rope by means of a

hitching device pinched to a metallic bar, which is attached to the axle of the said trucks; and the metallic bar thus attached passes down between the wheels through the opening in the 55 said track. A continuous wire rope fastened to the axle of said trucks is placed in the lower passage-way, which is constructed to any desired length, then upward and over a wheel, back through the upper way, and down over a 60 wheel to the starting point, the two ends of the rope being connected. The said tracks or bearings, having small wheels resting on the rails or tracks in the lower and upper passage-way or track, respectively, are provided as often 65 as necessary to carry the endless rope. The passage-way sufficient for one endless rope is designated a "section." The wheels at the ends of a section, over which said rope passes, are driven by a stationary engine or other power, (not shown,) thereby imparting a continuous 70 forward movement to the rope in the lower track, to which any towing-cable from boats may be connected. The rope will return in the upper track, which may be entirely in- 75 closed to protect it if desired.

My invention consists, also, in a capstan to be placed on one or both ends of the boat, on which the towing cable or line is wound, and from which it may be drawn with a uniformly-increasing tension, thereby giving a uniformly-increasing impulse to the boat until the velocity of the driving-rope has been attained. Any undesirable amount of line thus given out in starting the boat may again be 85 rewound on the capstan by the use of a crank provided therefor.

My improvement consists, further, in a device by which the end of the towing cable or line may be readily attached to the propelling-rope when in motion, and when the said device thus attached to the propelling-rope travels to the end of each section it detaches itself automatically, the boat being carried forward by its own momentum to the next section, 90 where the towing-line of the boat may be attached to the driving-rope of that section by means of the said device and continue thus from section to section throughout the length 95 of the canal.

In Fig. 1, A represents the lower track, and B represents the upper or return track, and 100

C C any suitable brackets, posts, or frames to support the said tracks.

d is a continuous wire rope, placed upon trucks e e, which trucks or wheels move upon 5 their respective tracks A and B. The said trucks are provided as often as necessary to carry the said wire rope. To the center of the axle of each one of the said trucks is attached a metallic bar, a, which projects 10 downward between the two rails of the lower track, A, which track is so constructed that a free opening is had beneath the driving-rope and between the rails of the said track A, so that the attaching device, which is fastened 15 to the end of the towing-cable from the boat, can be readily gripped or pinched onto the said metallic bar a. The said trucks are fastened to and carry the driving-rope.

E E are the wheels, placed at the ends of 20 each section, over which the endless rope passes, and from which it receives its constant motion, the said wheels being driven by means of an engine or any other way. (Not here shown.) The said wheels E E are so constructed 25 as to admit a free passage of rope and trucks, and also prevent the rope from slipping.

I do not confine myself to erecting my improved towing-track on the banks or sides of the canal, but may erect the posts in the center 30 and bed of the canal in such a manner that boats moving in one direction may pass on one side of the said posts and connect with the driving-rope on the track B, (which in this case would be constructed by the side of the 35 lower track, A,) and boats going in the opposite direction pass on the other side of the said posts and connect with the driving-rope on track A.

In Fig. 5, F F is a suitable frame, in which 40 the wheel or drum of my improved capstan is held. The wheel G has a deep groove formed in its edge, in which the towing cable or line f is wound. A stationary disk or flange, g, is placed loosely against one side of the wheel G, 45 against which it is pressed by means of the hand-wheel S and screw S', the said disk being prevented from turning by the spline v. The shaft on which the wheel G is fastened and rotates is provided on one end with a 50 crank, R, by which the said wheel may be turned to wind up the cable. A ratchet-wheel and pawl, k, are provided to hold it at any desired position. When the towing-cable is 55 wound on the wheel G, and it is desired to start a boat on which the said capstan and cable are placed, the end of the cable or towing-line is connected, by means of a device herein-after described, to the driving-rope or metallic bar a. The metallic bar a being connect- 60 ed to the trucks, which move with the rope, as already stated, therefore the end of the towing-cable thus attached to the metallic bar a moves with the driving-rope, which motion is uniform and continuous. As soon 65 then as the slack towing-line is taken up, the wheel G begins to give out additional line or

towing-cable, the friction disk or flange g resisting the free rotation of the wheel G, around which the towing line or cable is wound, thus imparting an impulse to the boat, and as the line unwinds and the diameter of its coil diminishes the impulse of the boat increases until the boat has attained the same speed of the driving-rope. Then the surplus line is again wound on the capstan-wheel G by means of 75 the crank R, and held in such position by the ratchet-wheel and pawl k. Fig. 4 is the device placed on the free end of towing cable or line. By means of the said device the towing cable or line is connected to the driving-rope 80 on track A.

The levers N N have their fulcrum n n in a case of two plates, one on each side of the said levers. On their short ends and inner sides hooks t t are formed to take hold of the metallic bar a. The longer legs of the said levers N N being closed together, the short ends open and admit the said metallic bar a. A peculiar-shaped bar, H, to which the free end of cable or towing-line is fastened, is placed between the long ends of the lever N N, close to their fulcrums and between said case or side plates. A pin passes through the said plates or case and bar, the hole in the said bar H being enlarged, so as to give a slight longitudinal 95 motion. The inner end of the said bar H has formed on its sides next the levers N N a projection, which in turn extends behind the corresponding legs or projections on the inner sides of the levers N N in such a manner that 100 any pull on the cable or said bar H causes the short ends or hooks of levers N N to be held closed firmly, and thereby holding to the metallic bar a and driving-rope. When the said fastening, however, has traveled to the end of 105 the section, and the long ends or legs or levers N N come between the stationary projections or lugs P P on lower track, A, Fig. 1, they are caused to close at the long ends and open at the short ends, thereby releasing themselves 110 and the towing-cable from the driving-rope automatically, the momentum of boat at same time carrying itself to the next section, where the cable or towing-line may again be connected, and the boat passed in like manner 115 through each successive section.

Having thus described my invention, what I claim as new, and wish to secure by Letters Patent, is—

1. In an apparatus for towing canal-boats, 120 the track A, provided with standard C, supporting cable-wheels E, in combination with an endless traveling cable provided with hitching-bars a, attached thereto, and having anti-friction wheels e, as and for the purposes described.

2. In an apparatus for towing canal-boats, the tracks A B, in combination with the standards C, carrying cable-wheels E E, and the endless driving-cable provided with metallic 130 hitching-bars a, as and for the purposes specified.

3. In an apparatus for towing canal-boats, the lower track, A, provided with a free opening between its parallel rails, and having formed therewith downwardly-extending lugs 5 or projections P P, adapted to receive the hitching and detaching device between them, as and for the purposes specified.
4. In an apparatus for propelling or towing canal-boats, the endless traveling cable provided with the hitching-bars, substantially as described, in combination with the pivoted hitching-levers N N, attached by means of the metallic bar a to the towing-cable f, and provided at the forward end with hooks t t, for engagement with the hitching-bars, substantially as described.
5. As a means for towing canal-boats, in combination with the hitching devices and towing-cable, substantially as described, the capstan-wheel G, provided with its flanged 20 friction-disk g, hand-wheel, and clamp-screw s, for operation upon said disk, and the ratchet-wheel and pawl k, located upon the main shaft of the capstan, as and for the purposes specified.

GEORGE R. TAYLOR.
